BACKUP PLATE FOR A PNEUMATIC VEHICLE IMPACT BUMPER

Wilbur L. Hiatt, 4508 Commonwealth Drive, Williamsburg Apt. N., Indianapolis, Ind. 46220

Filed May 6, 1971, Ser. No. 141,078

Term of patent 14 years

Int. Cl. D12—16

U.S. Cl. D14—6

Fig.1. Fig.2.

Fig.5.

FIG. 1 is a rear elevation of a backup plate for a pneumatic vehicle impact bumper of the present invention with the length of the plate extending vertically.

FIG. 2 is a top plan view of the structure illustrated in FIG. 1.

FIG. 3 is a front elevation of the backup plate of FIGS. 1 and 2.

FIG. 4 is an enlarged end elevation of the structure of FIGS. 1, 2 and 3.

FIG. 5 is an enlarged section taken along the line 5—5 of FIG. 1 in the direction of the arrows.

The bottom plan view of the structure is identical to FIG. 2.

The end of the structure opposite to the end illustrated in FIG. 4 is identical to the end illustrated in FIG. 4.

I claim:

The ornamental design for a backup plate for a pneumatic vehicle impact bumper, as shown and described.
